[57] CLAIM

The ornamental design for a combined pacifier and clip attachment, as shown and described.

DESCRIPTION

FIG. 1 is a perspective view of a combined pacifier and clip attachment showing the design of our invention;

FIG. 2 is a top plan view thereof;

FIG. 3 is a front view thereof;

FIG. 4 is a rear view thereof;

FIG. 5 is a right side view thereof; and,

FIG. 6 is a bottom view thereof;

The left side view is a mirror image of the right side view.
